UNITED STATES PATENT OFFICE.

JAMES C. WARREN, OF FREDERICKSBURG, VIRGINIA.

RECORDING MECHANISM.

1,300,525.

Specification of Letters Patent.

Patented Apr. 15, 1919.

Application filed October 15, 1917. Serial No. 196,738.

To all whom it may concern:

Be it known that I, JAMES C. WARREN, a citizen of the United States, and resident of Fredericksburg, Virginia, have invented 5 certain new and useful Improvements in Recording Mechanism, of which the following is a specification.

The invention relates to automatic recorders and is designed especially for recording 10 temperatures or pressures of steam or other fluids, and in carrying out the invention I have avoided the use of recording instruments requiring a supply of ink and a pen, these being objectionable, because of 15 the attention required in refilling, also because of the liability of the ink to flow too freely or not freely enough.

In carrying out my invention therefore I employ a perforating needle in connection 20 with a traveling tape which it punctures with small openings, the needle having in addition to its perforating movement a motion in a direction transversely of the tape to make it assume different positions in relation 25 to the lines of calibrations on the tape according to the variations in temperature or pressure which are to be recorded.

The invention consists in the features and combination and arrangement of parts hereinafter described and particularly pointed 30 out in the claims.

In the drawings:

Figure 1 is a diagrammatic view of the entire system.

Fig. 2 is a part view of the recording instrument with its box or container in section.

Fig. 3 is a plan view.

Fig. 4 is a plan view of a calibrated tape.

Fig. 5 is a diagram of a tape and an instrument adapted to make a plurality of records from different sources.

Fig. 6 is a vertical sectional view taken through the perforating mechanism in a direction longitudinally of the tape.

Fig. 7 is a part plan view and section of a part of the electro-magnet and showing the armature in section.

In these drawings the tape is shown at 1 running off from a spool through a die 2 carried by an arm 3 suitably supported, and 4 indicates a punch or needle which punctures the paper of the tape at the die. The tape is calibrated preferably after the manner shown in Fig. 4 having lines running lengthwise representing degrees of tempera-

ture and curved lines running transversely and representing time in hours and minutes. The stylus or needle is vertically disposed but it is carried to move in a direction transversely of the tape in a curved path. It and its immediate means for giving it its longitudinal stroke are carried by a swinging frame or arm 5 pivotally mounted at 6 in fixed bracket arms 7, the pivoted end of said punch carrier or frame 5 having an armature 8 mounted thereon, operating in connection with the field magnet 9 to swing the arm or frame and thus move the punch or needle in a curved path and in a direction transversely of the tape to the proper position to correspond with the pressure or temperature, at the moment prescribed, and having arrived at this position the needle is operated vertically or longitudinally to make a puncture in the tape, so that at the expiration of a prescribed period the tape will have a line of fine perforations appearing as dots on the tape.

Because the needle and its support swings in the arc of a circle from the point or center 6 the die 2 will be of curved form. The degree to which the frame or arm 5 with the needle carried thereby is deflected laterally of the tape will depend upon the current delivered to the field magnet and armature coil and this is determined by the degree of temperature or of the pressure of fluid to be recorded. For this purpose a resistance is interposed in circuit *a, b*, which includes the field magnet 9' and the shunt winding 8' of the armature, this circuit including also the battery 10. The resistance is shown at 11 and this is varied by a roller contact device 12 bearing and rolling upon the resistance bar, said roller being carried by an arm 13, said roller being pressed into firm contact with the resistance bar by a spring 14 bearing on the shank of the bracket carrying the roller and carried in a recess of the arm 13. 100 This arm is pivoted at 15 and it forms part of the electric circuit as does also the roller, one of the circuit wires being connected to the arm at 16 and the other to the end 17 of the resistance bar which forms a track for the roller. The arm 13 has a toothed segment 18 connected thereto, engaging a rack 19 on the rod 20 of a plunger or piston member 21 resting on the body of mercury 22 in the casing 23 which mercury body is representative of any medium, the movement of or change in which is to be recorded as a

result of variations of temperature and pressure, the effect being to shift the trolley roll on the resistance bar and thus increase or decrease the resistance and so modify the 5 current to the field magnet and armature winding to cause a movement of the armature to accord with these changes and consequently a swinging movement of the arm or frame 5 about the pivots 6 and of the 10 punch or needle 4 along a curved path transversely of the calibrated tape 1.

The armature is specially constructed and arranged relative to the field magnet. It 15 consists of a cylindrical body which as shown in the plan view is provided with recesses extending in its sides, leaving major and minor body portions 8^a, 8^b connected by a neck portion 8^c, the armature winding surrounding this neck portion and lying between the main body portion and the minor body portion 8^b.

The normal position of the frame 5 with the armature 8 is such that one corner of the major body portion thereof is just within 20 the range of the lines of force emanating from the field magnet. The frame or arm 5 at this time, that is when in inactive or normal position is lying at an inclination to the plane of movement of the tape, it being so positioned by the spring 8^d. When the 25 field magnet is energized the armature is turned and the punch carrying arm or frame is moved in a direction transversely of the tape.

30 The tape is advanced by a substantially continuous movement, by feed rolls, that marked 24 being driven through suitable means, as for instance a clockwork mechanism and the one marked 25 being a weight 35 roller having its axis mounted in a vertical slot 26 of a suitable frame.

The clockwork mechanism also controls the periods of operation of the punch or needle 4 for which purpose a commutator is 40 used as at 27, rotating about an axis 28 and having insulating segments indicated by the black parts 29 and conducting segments at 30, the commutator segments being borne upon by the brushes 31, so that when these 45 are in contact with the conducting segments the current will be completed through the circuit *c*, *d* from battery 10' and the arrangement is such that this circuit will be closed every thirty seconds and the punch 50 will be operated and thus the tape will be punctured with a line of fine perforations.

When the circuit is closed the current will pass through the lower pivot bearing 6, the 55 frame or arm 5, the arm or bracket 5' attached thereto and thence through the contact 32 fixed on the bracket and the movable contact 33 carried by the plate or arm 34, the conducting spring 35 and post 36 carried by the frame or arm 5, and thence to the 60 solenoid coil 37 carried by the said frame or

arm 5, and thence to the battery. The energizing of this solenoid coil will draw up the core 38 and as this carries the punch or needle 39 at its upper end the paper tape will be punctured. The upward movement 70 of the solenoid core and needle is cushioned and arrested by a spring 40 surrounding a rod 41, depending from the arm or frame, 5, the said rod acting as a guide for an arm 42 fixed to and extending laterally from the 75 needle rod or solenoid core 38. This arm slips freely on the depending rod 41 and at the upper end of its movement it strikes the spring 40 and is arrested and cushioned thereby. The arm 42 has an extension 42' at 80 its right hand end which as the needle approaches the upper limit of its stroke strikes against the arm 34 and lifts the same, together with the contact member 33, thus breaking the circuit to the solenoid 37, 85 which being deenergized will allow the needle or core 38 to fall, this action being rendered certain because the core has a weight at 43 and also because the spring 40 tends to throw the arm 42 with the core or needle, 90 downwardly. Besides breaking the circuit to the solenoid coil 37 the lifting of the arm 34 also has another function, namely, it slightly lifts the solenoid core 44 into the field of solenoid coil 45 through which coil 95 the current now flows through wire 46, owing to the breaking of the circuit at 32, 33, it being understood that the coil 45 is wound with finer wire and thus presents a higher resistance to the passage of the current than the path first mentioned namely 100 bracket 5', contacts 32, 33, spring 35, post 36 and coil 37 but when this part of the circuit is broken the current takes the high resistance path 46 and coil 45 and this pulls up 105 the solenoid 44 and keeps the circuit broken at 33, 34, until the commutator 27 breaks the punch circuit, when the core 44 together with arm 34 and contact 33 therefor will be restored ready for the next action.

110 A weight 46' aids in restoring the core 44, arm 34 and contact 33 to normal position. The solenoid coil 45 is connected with the post 36 by wire 45^x and consequently with the needle coil 37, but being of high resistance in respect to the resistance of the coil 37 the latter is not energized sufficiently to give the needle an upward movement when the coil 45 is in circuit.

115 The commutator is driven by the same clock mechanism as the tape feed rolls and consequently the operations of the needles take place in definite relation to the feed of the tape. Instead of a mercury body and float as a temperature affected device I may employ a thermostat.

120 In Fig. 5 I show a form of the invention adapted to make a plurality of records from different sources, such as from different rooms in a building or manufacturing plant 130

and in carrying out this part of the invention two or more independent tapes may be arranged side by side or one wide tape may be employed to receive the strokes from the 5 needles, which with their operating means are arranged side by side. The wide tape or the plurality of independent tapes, if such be used, will be fed by mechanism substantially like that described above, the feed rolls 10 being long enough to take the wide tape or the whole number of independent tapes. Where a wide tape is employed the transverse lines representing the divisions of 15 time will be in plural series, each series corresponding in the extent of their arc shape to the lateral throw of the needle which is to puncture this portion of the tape. The wide tape may have its calibrations intended for one needle different from those intended for the other needle or needles according to the 20 character of the changes to be recorded. The same clockwork mechanism may be used, common to both portions of the wide tape or to the independent tapes and the same commutator 25 may be employed and in large part the same circuit connections from this commutator to the battery and to the solenoids of the different units. The clockwork mechanism is of the self winding type.

30 The instrument is held within a suitable covering, preferably glass inclosed and in order that it may be in a true horizontal position I provide adjustable feet at 50, which when adjusted are fixed in position by nuts 35 50'. The tape is directed by guides 51.

What I claim is:—

1. In combination a moving tape, a marking device, electro-magnetic means for giving said device its marking movement, an 40 arm carrying said device and its electro-magnetic means, said arm being pivotally mounted, an armature mounted at the piv-

oted end of the said arm, a field magnet acting upon the said armature, and a controller affected by the changes in the condition to 45 be recorded and regulating the supply of current to the field magnet, and also to the armature, substantially as described.

2. In combination a moving tape, a marking device, a carrier for said marking device, electro-magnetic means for operating the said carrier to shift it from place to place relative to the tape, a controller in circuit with the electro-magnetic device, said controller comprising a variable resistance 50 and means affected by the changes in the condition to be recorded for adjusting the said resistance, substantially as described.

3. In combination a tape, feed rolls for said tape, a marking device, an electro-magnetic means for operating the marking device, a commutator for energizing the said electro-magnetic means periodically, clockwork mechanism for operating said commutator, and said feed rolls, a carrier for the 60 marking device, electro-magnetic means for shifting the carrier and a controller affected by changes in the condition to be recorded 65 for regulating the supply of current to said electro-magnetic carrier operating means, 70 substantially as described.

4. In combination with a moving tape, a marking device, a carrier therefor, electro-magnetic means for shifting the carrier, a moving contact and a track for said moving contact in circuit with the electro-magnetic means, whereby the resistance of said 75 circuit is changed and a controller for the movable contact affected by changes in the condition to be recorded, substantially as 80 described.

In testimony whereof, I affix my signature.

JAMES C. WARREN.
